ADJUSTABLE GRINDING DISC

Adolf Ditting and Walter Engi, Zurich, Switzerland;
said Engi assignor to said Ditting

Application November 8, 1954, Serial No. 467,477

Claims priority, application Switzerland
November 13, 1953

1 Claim. (Cl. 241—259)

The present invention relates to a device for the adjustment of grinding discs in coffee and spice grinders. In such grinders, accurate adjustment of the grinding discs to ensure the desired grinding fineness is of particular importance. Since the grinding discs will wear away, it must be possible to readjust them in order to reproduce the desired grinding fineness. The present invention has for its object to fulfill this requirement by simple means.

This invention is characterized by the fact that the displaceable grinding disc is mounted on a shaft arranged so as to be rotatable but axially undisplaceable in a bushing which in turn is axially displaceable but not rotatable in the grinder housing and equipped with a fine thread on which a stop ring formed as a gear and ring nut is arranged, which is forced against a surface of the housing by means of a pressure spring, and that a gear mounted on an axially displaceable shaft projecting into the grinder housing and rotatable by means of a handle, meshes with the teeth of the stop ring so that rotation of the handle permits the grinding fineness to be adjusted while retraction and rotation of the shaft permits the tooth engagement to be altered.

An embodiment of the invention is shown in the enclosed drawings, in which:

Fig. 1 is a vertical section of the grinder, and

Fig. 2 is a section along line I—I in Fig. 1.

The grinder is provided with a base 1 to which the grinder housing 2 is attached by means of screws 1a. The axle 3 forming the motor shaft on which is mounted the grinding disc 4 is axially displaceable in ball bearings 5 and 6 mounted in the guide bushing 7 and base 1 respectively. The guide bushing 7 is displaceably arranged in the housing 2 and secured against rotation by wedge 8. The lower portion of this guide bushing is equipped with a fine thread 7a onto which a ring 9 is screwed. This ring is provided with teeth 10 and forms a gear. A 50 circlip 12 secures a disc 13 to the guide bushing 7, and

2

springs 14 supported in the housing 2 act on the disc 13 so as to force the guide bushing 7 upwards so that ring 9 engages the housing surface 2a. The ring 9 limits the extreme raised position of the grinding disc 4, which gives against the action of the springs 14 if, by way of example, hard particles appear between the grinding discs. The teeth 10 of ring 9 are engaged by a cup-wheel type gear 16 on shaft 17, which projects into the housing 2 and is supported at 2b and 2c. A knob 18 is mounted at the upper end of the shaft 17, and the said knob is equipped with a scale 19. The shaft 17 is depressed by means of pressure spring 20 so that the wheel 16 permanently meshes with the teeth of ring 9. Rotation of the knob 18 turns ring 9 forward and backward on the guide bushing 7 thereby setting the distance between the rotary grinding disc 4 and the stationary grinding disc 22. As shown in Fig. 2, a rib 2e is arranged in the housing portion 2c, while a pin 17a is inserted in the shaft 17 so that the shaft is free to perform about one revolution only, which 20 determines the maximum distance between the grinding discs.

If the two grinding discs are worn so that the finest grinding distance is not obtained at the 0 position of rotating knob 18, the shaft 17 is retracted against the action of spring 20. The gear 16 is disengaged and by turning the engagement can be altered so that the original grinding fineness can again be set by rotating the knob 18.

Having now particularly described and ascertained the nature of our said invention and in what manner the same 30 is to be performed, we declare that what we claim is:

In a coffee and spice grinder, a housing, a bearing firmly mounted within said housing, a grinding disc firmly mounted in said housing, a rotary shaft carried by said bearing, another grinding disc carried by said shaft and 35 cooperating with the first-mentioned grinding disc, a guide bushing displaceably mounted in said housing for guiding said shaft means securing said guide bushing against rotation, said guide bushing having a threaded portion, an annular gear carried by said threaded portion, a spring 40 pressing against said guide bushing, another gear meshing with the first-mentioned gear, an axially displaceable shaft carrying said other gear, and a handle carried by the last-mentioned gear.
